(57) CLAIM

The ornamental design for a cleaning pad with pattern, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top plan view of a first embodiment of a cleaning pad with pattern showing my new design; and,

FIG. 2 is a top plan view of a second embodiment of the cleaning pad with pattern showing my new design.
